UNITED STATES PATENT OFFICE.

GEORGE W. BROWN, OF CAPE ELIZABETH, MAINE, ASSIGNOR, BY DIRECT AND MESNE ASSIGNMENTS, OF ONE-HALF TO SUSAN J. DODGE, OF DAMARISCOTTA, MAINE, AND ONE-HALF TO EMMA BROWN, OF CAPE ELIZABETH, MAINE.

PENCIL SHARPENER.

Application filed March 1, 1926. Serial No. 91,500.

My invention relates to pencil sharpeners and more particularly to that type employing a keen cutting-edge blade to produce the proper point on the pencil.

5 One of the principal difficulties heretofore met with in the use of sharpeners with blade cutters has been the tendency of breaking the lead point during the cutting operation.

I have, for one of my objects, sought to 10 overcome this trouble by providing a support, not alone for the wood portion of the pencil, but for the whole length of the lead point upon which the cutting operation is being performed.

15 In my sharpener a large proportion of the tapered portion of the pencil has circumferential support or backing to resist the cutting thrust of the blade, the latter not extending beyond the end of the lead which is left in a somewhat blunt point.

Another deficiency characteristic of the conventional type of blade sharpeners is the lack of means to extract the short piece of 20 lead after it has been broken off in the sharpener and become strongly wedged between the knife and the wall of the sharpener.

While the breakage of the lead is of infrequent occurrence in the manipulation of my sharpener, still, the possibility of experiencing this trouble is always present, and for that reason I have provided means to meet this contingency. I employ a small propelling plunger which is always in position adjacent the end of the cutting chamber and by a slight movement inwardly of this plunger a piece of the lead broken off from the main portion of the lead in the pencil may be dislodged from the small end of the tapered chamber in the sharpener in which it had become firmly wedged.

40 A still further object pertains to the aligning of the pencil previous to the cutting operation, whereby when this work is completed it may result in the procurement of a tapered pencil end with the lead symmetrically pointed and the wood evenly cut on all sides of the lead at a uniform distance from the point thereof. Without this preliminary guidance, starting the cut concentrically, the 45 above object is difficult of attainment.

With these and other objects in view the invention consists in the novel features hereinafter described in the specification, and in

the accompanying drawings in which the preferred embodiment of my invention is illustrated,—

Fig. 1 is a perspective view of my sharpener as applied to a block type thereof;

Fig. 2 is a plan view of the same;

Fig. 3 is an enlarged section of the sharpener, taken on line 3—3, Fig. 2;

Fig. 4 is a transverse section of the same taken on line 4—4, Fig. 2;

Fig. 5 is an enlarged section taken on line 5—5, Fig. 3;

Fig. 6 is a plan view of the sharpener as applied to a pencil holder;

Fig. 7 is an enlarged view of the latter, in section, which is taken on line 7—7, Fig. 6;

Fig. 8 is a view of the blank from which is made the plunger and carrier for the projector shown in Fig. 7;

Fig. 9 shows the completely formed element shown in Fig. 8;

Fig. 10 is an enlarged section taken on line 10—10, Fig. 7;

Fig. 11 is a fragmentary sectional view, transversely of the sharpener, greatly enlarged, taken on line 5—5, Fig. 3, and showing the superior support or backing for the lead point when cutting is taking place;

Fig. 12 is a fragmentary sectional view, greatly enlarged, taken on a vertical plane coincident with the axis of the pencil and plunger and shows the position of these two elements and the cutting blade, relatively, and

Fig. 13 shows an alternative method of mounting the plunger.

In all views, like characters of reference 90 refer to similar parts.

In Figs. 1 and 6 are shown two different applications of my sharpener, employing, however, equivalent elements in each case.

In Fig. 1 I have illustrated my sharpener in block form, the block 1 being constructed of either of various materials, as wood, metal or any one of the numerous plastic substances, such as fiber, vulcanized rubber or fixture cement.

In either case its construction follows closely the design illustrated in sectional detail in Fig. 3. From one end of the block 1 a straight hole 2 extends inwardly for a spaced distance or sufficiently far to provide an outside bearing for the straight portion 2'

of the pencil and to locate and hold the latter at the correct angular relation with the cutting blade. The pencil thus confined may not wobble and cause a greater cut to be made on one side than on the other.

5 3 is the cutting blade which is mounted on the block so that the end which starts the cut is abreast of the interior end of the straight hole 2 from which latter point the cutting 10 chamber 4 starts on a taper predetermined for the pencil point 4'.

It will be observed that the interior wall 15 of the cutting chamber 4 describes a straight sided frustro-conical figure with the small end 5 identically the same in size as the 20 diameter of the finished point of the lead. The tapered portion of the pencil, both wood and lead, consequently has a constant support and backing whenever either is or both 25 are in contact with the cutting blade, and this support continues until the very end of the lead is formed to the final shape.

Referring to Figs. 3 and 5 it will be seen 30 that the lead, even to the extreme end of the point, is supported and held against the cutting thrust of the blade by considerably more than a semi-circular portion of the 35 wall of the cutting chamber, or in other words, more than half of the peripheral surface of the lead has a perfect seat on the interior of the frustro-conical shaped cutting chamber against which it may bear while the blade is operating on it, and under this 40 condition there is little likelihood that breakage of the lead will occur.

The diameter of the small end of the cutting chamber, as seen at 5, depends on the predetermined size desired for the point of the lead. As I stated in my preamble a 45 somewhat blunt point is best suited for all practical purposes, so I construct the blade of such length that it will cut no further than the small end of the tapered portion of the cutting chamber. This produces a point very much stronger than a needle point and somewhat smaller than the thin leads quite generally used in the present day propelling pencils.

Extending outwardly from the small end 50 of the frustro-conical cutting chamber 4 is a hole 8, made substantially the same size as the small end 5, which is also the size of the finished lead point, and operating in this hole is a plunger 9 which, should the occasion require, serves to force back into the tapered chamber the piece of lead which may have broken off during the cutting operation.

It will be seen, by reference to Figs. 11 60 and 12, that the plunger 9 may also serve, when reciprocated backwardly and forwardly, to smooth out any burrs or turned over portions of the edge of the blade 3, incident to the cutting of the lead which 65 oftentimes is somewhat gritty in its nature.

This plunger may be secured in operative position in the hole 8 in any approved manner but I have elected to make it, in the case of the block sharpener, integral with a yielding extension 10, which latter I fixedly 70 secure in the block.

In Figs. 6 and 7 my device as illustrated shows it mounted on and a part of a pencil holder. The body 1 of this holder has provision for the reception and guidance of the 75 pencil similar to that in the block type of sharpener described, and the action of the cutter is exactly the same.

The plunger is, in this latter design made a part of a split collar 12 which is slidably 80 positioned within the bore of the holder sleeve 13. The function of the plunger remains the same as that of the block sharpener plunger, but its actuation may be accomplished by means of the projecting lip 85 12' extending outwardly from the split ring 12. A slight pressure on the lip moves the plunger into or out of the cutting chamber,— its inward movement having the effect of dislodging any broken pieces of lead should 90 this situation develop.

Indent 14 extending into the interior of the sleeve 13 restrict the movement of the split ring 12 outwardly so as to prevent the 95 complete withdrawal of the plunger 9 from out of the hole 8. These indents may properly be made in the sleeve subsequently to the insertion of the split ring thereinto.

So as to utilize the sleeve 13 to hold pencils varying slightly in diameter I cut a 100 scarf 15 longitudinally thereof, making it somewhat resilient, and I also make this scarf serve as keying means for the lip 12'.

In Figs. 8 and 9 I illustrate the blank and the finished formed split collar 12, respectively. I prefer this construction on account of the low cost of manufacture.

It is quite desirable at times to have the sharpener within easy reach of the user. In the case of the pencil holder type of sharpener, shown in Figs. 6 and 7, this desideratum is satisfied by mounting it on a pencil which will be carried in the user's pocket. In the block form, shown in Figs. 1 and 3, the loop 16, to which a cord or ribbon may be attached, provides a handy and convenient method of securing the sharpener so that it will be instantly accessible. Or it may be attached to a watch chain to anchor one end in the owner's vest pocket.

In Fig. 13 I illustrate a somewhat different method of mounting the plunger 9 from that shown in Fig. 1. On the surface of the block 1, beneath the blade 3, is a depression 1' within which the extension 10 from the plunger 9 may reciprocate. The bent-over end 10' operating in the depression space 1" restricts the movement of the member 10 outwardly by its abutting on the side wall of the depression, and this restriction prevents 120 125 130

the plunger 9 from completely withdrawing from out of the hole 8.

The operation of the sharpener may be clearly understood by the reading of the foregoing description especially when taken in connection with the several illustrations. The cutting operation should be stopped when the extreme end of the lead reaches the outer end of the blade. Further cutting will produce no finer point and wastage of the pencil results if the operation is continued. The whole length of the cut is visible to the operator and it is thus easily ascertained when to desist cutting.

15 The preeminent features of my sharpener are, briefly stated, the ability to support the pencil and give it backing along the whole length of the taper being cut, even to the extreme end of the lead, as at "a", 20 Fig. 3, thereby largely eliminating the trouble of breakage of points; the provision for removing from the small end of the tapering cutting chamber any piece of lead which may have been broken off and become 25 lodged therein; and the ability to properly align the pencil in the sharpener relative to the correct angular relationship with the blade before the start of the cutting operation.

30 And it may be pertinent to state at this time that while the most annoying trouble with pencil pointers is their tendency to break the point of the lead when nearly formed, it is not always caused by faulty 35 design or construction. Much inferior and defective material is marketed,—such as pencils which are made up of small pieces of lead, cross-grained stock and bent leads

which break as they are assembled in the pencil bodies.

The prime cause, however, when the average grade pencil is used, for the breakage of the point arises from the fact that the lead is not properly supported at the extreme end when being formed into the desired point. In this respect I believe my sharpener will fill a long-felt want and provide a most efficient and satisfactory appliance.

Having thus described my invention what I claim is:

1. In a sharpener of the class described, a guide provided with an open-ended, straight-side tapering chamber having an elongated length-wise slot through its wall, 55 said chamber communicating, at its smaller end, with an opening disposed at an angle to the axis of said chamber and in a plane parallel to one of the sides thereof, a cutting-blade operable through said elongated slot 60 and effective over the full length, only, of the side of said tapering chamber, and a plunger reciprocable in said opening and operable in close and parallel relation to, and inwardly of, said cutting-blade. 65

2. In a sharpener of the class described, a guide having a smooth, straight-sided tapering chamber open at both ends and having an elongated, length-wise slot through the wall thereof, and a cutting 70 blade, operable through said elongated slot and coextensive with the tapered chamber, terminating at the apex of the tapered chamber whereby it is effective over the entire length only of said tapering chamber.

GEORGE W. BROWN.
